UNITED STATES PATENT OFFICE.

FREDERICK WM. ORTH, OF PORTLAND, OREGON.

MEAT-CHOPPING MACHINE.

No. 853,894.

Specification of Letters Patent.

Patented May 14, 1907.

Application filed December 7, 1904. Serial No. 235,838.

To all whom it may concern:

Be it known that I, FREDERICK WILLIAM ORTH, a citizen of the United States, and a resident of Portland, in the county of Multnomah and State of Oregon, have invented a new and useful Improvement in Meat-Chopping Machines, of which the following is a specification, reference being had to the accompanying drawings as constituting a part thereof.

My invention has for its object to obtain a machine, which shall embody the features and combinations hereinafter described and claimed, with the end in view of obtaining an efficient device, which is convenient to use in butchershops and restaurants, and also for family purposes. Furthermore, a machine which may be built and sold at a reasonable figure.

In the drawings, Figure 1, is a front elevation of my machine; Fig. 2, is an elevation looking in the direction pointed by the arrow, shown in Fig. 1; Fig. 3, is a partial plan section taken on a line A—A, of Fig. 2; Fig. 4, is a plan section on a line B, of Fig. 1; Figs. 5 and 6, are details of the hanger *h*; Figs. 7 and 8, are details of the pitman, operating the lever *o*; Fig. 9, is an enlarged section of the bearing for the reciprocating rod *q*, and; Fig. 10, is a perspective of one of the knives *r*.

The letters designate the parts referred to.

My machine comprises a base consisting of a semi-circular casing *a*, made of sheet iron and provided with a flange-like bottom edge *a'*, perforated to receive screws by which to fasten the same upon a table or other support. On the back of the casing is riveted a box *b*, in which to receive and adjustably support the standard *c*.

The standard is arranged to be vertically adjusted, so as to properly position the knives with respect to the chopping block *x*. For this purpose, the bottom end of the standard *c* is made with a threaded cavity *c'*, in which to receive a screw *d*, resting on the bottom of the box *b*. To hold the screw *d* in place, the same is journaled in diaphragms *e e'*, the upper one of which, *e'*, being made quite heavy, because against it abuts the integral collar *d'*, provided on the screw *d* for turning the same. The diaphragm *e'* has to sustain the shock of the impact of the knives upon the chopping block. The collar *d'* is conveniently made with series of holes, in which to insert a rod or other instrument, by

which to turn the screw *d*, so as to adjust the standard *c* up and down.

In the perpendicular member of the standard *c* is journaled an internal gear-wheel *f*, provided with a handle *f'*. Above the axle 60 of the wheel *f* there is journaled in the standard *c* one of the ends of the crank-shaft *g*, the opposite end of which shaft is journaled in the hanger *h*. Details of the construction of such hanger are shown in Figs. 5 and 6. The 65 upper end of the hanger *h* is made with a threaded shank *h'*, inserted in a threaded aperture therefor made in the upper horizontal member of the standard *c*; and the hanger *h* is given additional rigidity by means of a nut 70 *i*. The lower end of the hanger *h* is made with the hinged part *h''*, constituting the lower half of the box in which is journaled the inner end of the crank-shaft *g*. The hinged half *h''* is secured to the bottom of the 75 main body of the hanger *h* by a bolt and nut *j*, inserted through holes therefor made in projecting lips on the meeting faces of the two halves of said box.

On the crank-arm *g*, is affixed a pinion *k*, 80 meshing with the internal gear of the wheel *f*. On the inner end of the crank-arm *g* is mounted a fixed collar *l*, and a cam *m*. Said cam is made with a groove on its periphery, in which to receive the strap of the pitman-rod *n*, which pitman-rod is pivotally connected with the lower end of a lever *o*, pivotally supported in a bracket *o'*, projecting from the upper member of the standard *c*.

In the upper extremity of the members *c* 90 is made an eye or box, having a thread in which is inserted the threaded end of a pipe *p*, serving as a guide bearing for a vertically reciprocating rod *q*. To avoid an undue friction, the pipe *p* is made with diaphragms 95 *p'* at its two ends, in which the rod *q* reciprocates; and there are furthermore, diaphragms *p''* provided, incidentally serving as bearings for the rod *q* too, but mainly functioning to provide a sort of an oil box for lubricating 100 the rod *q*. For this purpose, the pipe *p* is made with an opening *p³*, through which waste is introduced, between the diaphragms *p''*, and packed about reciprocating rod *q*, and a hole *p⁴* is provided through which to introduce lubricant. The upper diaphragm *p''* allowing the same to trickle through onto the packing between the two diaphragms *p''*, and the lubricant is absorbed in such packing. The idea being to furnish sufficient lubricant 110

for the reciprocating rod q , but at the same time to prevent the lubricant trickling down such reciprocating rod on to the knives r . On the reciprocating rod q , above the extremity of the upper member of the standard c is journaled on the rod q crown-wheel s , provided with a peripheral groove s' in which to receive the forked end of a yoke t , by which the crown-wheel is held against vertical displacement.

The reciprocating rod q is made with a longitudinal groove q' , and the hub of the crown-wheel s is provided with a stud-screw s^2 , the point of which enters the groove q' , and in so doing provides an operative connection between the crown-wheel s and the reciprocating rod q , allowing the latter to be reciprocated in the hub of the crown-wheel, and at the same time causing said rod to be progressively rotated by the progressive revolution of said crown-wheel.

The rotation of the crown-wheel s is effected by means of a pawl u , pivoted to the upper end of the lever o . In each movement of the lever o , due to the action of pitman n , the pawl u is moved from one tooth of the crown-wheel to another, and as the action of the rod o is reversed the pawl u will move the crown-wheel, and therewith the rod q and the knives supported from the lower end of the rod q , a distance equal to the length of a tooth of the crown-wheel. The object of this construction is to cause the knives r to operate over the entire surface of the chopping block. The rod q is reciprocated by means of a link v , the upper end of which is connected with the crank end g' of the shaft g , and the lower end of which link is secured on the stud-pin w' of a collar w , inserted between a fixed collar q^2 and a movable collar q^3 on the lower end of the rod q .

To the lower extremity of the rod q is rigidly affixed a bar y , made with a series of the transverse slots y' in which to receive the ribs r' of the knives r . The knives are clamped in place by means of set-screws z ; and in order to facilitate the adjustment of the knives they are respectively provided with collars r^2 so positioned that when the ribs r' of the knives are inserted in the slots y' of the bar y the ribs r^2 will abut against the side of the bar, when the knives have been put in their proper position; after which the knives may be secured by means of the set-screws z .

Within the annular casing a of the base of my machine is inserted a wooden chopping block x . To secure the chopping block in place I provide the same with stud-pins 2 , on opposite sides, arranged to be inserted in slots a^2 , the ends of the casing a , and to be engaged by hooks 3 . On the upper part of the block a is affixed a rim 4 to hold the material being operated upon on the chopping block.

The set-screw 5 is provided to clamp the base of the standard c in place when properly adjusted as to height.

I claim:

1. A chopping machine comprising a base 70 consisting of a semi-circular casing, provided with means for fastening the same to a support; a box or socket b affixed to the back of said casing; a standard c , and means supporting the same in said socket so as to render the same vertically adjustable; a hanger h , a crank shaft g , journaled in said standard and said hanger; a gear-wheel f , journaled in said standard, and a pinion on the shaft g meshing with such gear-wheel; a vertically 75 reciprocable rod q journaled in the upper end of the standard c , and having a longitudinal groove q' ; an operative connection between the rod q and the crank-end of the shaft g ; means operated by the rotation of the shaft g , adapted to progressively turn the rod q ; a bar affixed to the lower end of the reciprocating rod, and a plurality of knives movably secured to said bar.

2. A chopping machine comprising a base 90 consisting of a semi-circular casing, provided with means for fastening the same to a support; a box or socket b affixed to the back of said casing; a standard c , and means supporting the same in said socket, so as to render the same vertically adjustable; a hanger h , a crank shaft g , journaled in said standard and said hanger; a gear-wheel f , journaled in said standard, and a pinion on the shaft g meshing with such gear-wheel; a vertically reciprocable rod q , journaled in the upper end of the standard c , and having a longitudinal groove q' ; an operative connection between the rod q and the crank end of the shaft g ; a crown-wheel s journaled on the rod q , and having a stud s^2 entering the said slot of said rod; means for holding the crown wheel against vertical displacement; a pitman on the shaft g , a lever o operated by said pitman, a pawl pivoted to the upper end of the said lever, and arranged to engage with and rotate the crank wheel; a bar affixed to the lower end of the reciprocating rod, and a plurality of knives movably secured to said bar.

3. A chopping machine comprising a base 115 consisting of a semi-circular casing, provided with means for fastening the same to a support; a box or socket b , affixed to the back of said casing; diaphragms in the lower end of said socket; a screw d journaled in said diaphragms, said screw being made with a collar, or nut, by which to turn the same; a standard c , having a threaded cavity c' , which standard is adjustably supported by said screw d in said socket b ; a hanger h , a crank shaft g , journaled in said standard and said hanger; a gear-wheel f , journaled in said standard, and a pinion on the shaft g meshing with such gear-wheel; a vertically reciprocable rod q , journaled in the upper end of the 125 130

standard *c*, and having a longitudinal groove *q'*; an operative connection between the rod *q* and the crank-end of the shaft *g*; a crown-wheel *s* journaled on the rod *q*, and having a stud *s*² entering the said slot of the said rod; means for holding the crown wheel against vertical displacement; a pitman on the shaft *g*, a lever *o* operated by said pitman, a pawl pivoted to the upper end of said lever, and arranged to engage with and rotate the crown wheel; a bar affixed to the lower end of the reciprocating rod, and a plurality of knives movably secured to said bar.

4. A chopping machine comprising a base consisting of a semi-circular casing, provided with means for fastening the same to a support; a box or socket *b*, affixed to the back of said casing; diaphragms in the lower end of said socket; a screw *d* journaled in said diaphragms, said screw being made with a collar, or nut, by which to turn the same; a standard *c*, having a threaded cavity *c'*, which standard is adjustably supported by said screw *d* in said socket *b*; a hanger *h*, a crank shaft *g*, journaled in said standard and said hanger; a gear-wheel *f*, journaled in said standard, and a pinion on the shaft *g* meshing with such gear-wheel, a tubular bearing *p*, affixed in the upper extremity of the standard *c*, and provided with diaphragms *p'* at its two ends, a vertically reciprocable rod *q* journaled in said tubular bearing being further provided with diaphragms *p*², for the purpose specified, an operative connection between the rod *q* and the crank end of the shaft *g*, a crown-wheel journaled on the rod *q*, and having stud *s*² inserted in a slot *q'* of said rod *q*; a yoke *t*, secured in the standard and arranged in a slot provided in the hub of said crown wheel so as to hold the latter against vertical displacement, a pitman on the shaft *g*, a lever *o*, operated by said pitman, a pawl pivoted to the upper end of said lever, and arranged to engage with and rotate the crown wheel, a bar *y* affixed to the lower end of the reciprocating rod *q*, and provided with a series of transverse slots *y'*, a plurality of knives made with ribs *r'*, inserted in said slots of the bar *y*, set-screws on the bars for clamping the knives in place.

5. A chopping machine comprising a base consisting of a semi-circular casing, provided with means for fastening the same to a support, a chopping block and means for securing the same in said casing; a socket *b* affixed to the back of said casing, diaphragms in the lower end of said socket, a screw *d* journaled in said diaphragm, said screw being made with a collar or nut, by which to turn the same and standard *c*, having a threaded cavity *c'*, which standard is adjustably supported by said screw *d* in said socket *b*, a hanger *h*, a crank shaft *g*, journaled in said standard in said hanger, a gear-wheel *f*, journaled in said standard, and a pinion on the shaft *g*, meshing with such gear-wheel, a tubular bearing *p*, affixed in the upper extremity of the standard *c*, and provided with diaphragms *p'* at its two ends, a vertically reciprocable rod *q* journaled in said tubular bearing being further provided with diaphragms *p*², for the purpose specified, an operative connection between the rod *q* and the crank end of the shaft *g*, a crown-wheel journaled on the rod *q*, and having stud *s*² inserted in a slot *q'* of said rod *q*; a yoke *t*, secured in the standard and arranged in a slot provided in the hub of said crown wheel so as to hold the latter against vertical displacement, a pitman on the shaft *g*, a lever *o*, operated by said pitman, a pawl pivoted to the upper end of said lever, and arranged to engage with and rotate the crown wheel, a bar *y* affixed to the lower end of the reciprocating rod *q*, and provided with a series of transverse slots *y'*, a plurality of knives made with ribs *r'*, inserted in said slots of the bar *y*, set-screws on the bars for clamping the knives in place.

In testimony whereof, I have hereunto affixed my signature in the presence of two witnesses.

FREDERICK WM. ORTH.
